E. K. Bond

UNITED STATES PATENT OFFICE.

ARTHUR McCALLAN, OF OTTAWA, ONTARIO, CANADA.

DUSTPAN.

1,384,076.

Specification of Letters Patent. Patented July 12, 1921.

Application filed January 29, 1921. Serial No. 440,912.

To all whom it may concern:

Be it known that I, ARTHUR McCALLAN, a citizen of the Dominion of Canada, residing at Ottawa, in the county of Carleton 5 and Province of Ontario, have invented certain new and useful Improvements in Dustpans, of which the following is a specification.

The present invention relates to improvements in dust pans or the like and the principal object is to provide a device of the character described, which is provided with resilient means for causing the open edge portion of the same to adhere to the surface 15 during the sweeping of dust and refuse thereinto.

Another object is to provide a dust pan, having a strip of resilient material, such as rubber detachably connected to its front 20 edge to provide a close union of the pan with the floor or surface during the sweeping operation.

With these and other objects in view, the invention consists in the construction, combination and arrangements of parts as will be hereinafter fully described, illustrated in the accompanying drawings, and pointed out in the claim hereunto appended.

Figure 1 is a perspective view of the improved dust pan.

Fig. 2 is a fragmental vertical section through the pan base and attachment, illustrating the connecting means for the latter.

Fig. 3 is a magnified fragmental view of a modified means for attaching the strip to the pan base.

Fig. 4 is a fragmental vertical section on line 4-4 of Fig. 2 and

Fig. 5 is a section on line 5-5 of Fig. 2, 40 illustrating the holding elements.

Referring to the drawings like numerals designate like parts in the various drawings.

As is well known the ordinary dust pan 45 is not entirely effective in gathering up sweeping and particularly dust, by reason of the failure of the pan to be held in close relationship to the floor and resultantly all of the dust is not swept into the pan.

The improved device comprises a pan, having base and flange portions 5 and 6 and a handle 7, which extends through the flange 6 and is secured by a rivet 8 to the said base portion 5.

Connected to the front edge 9 of the pan base 5, by soldering is an elongated metallic

U-shaped channel member 10, the outer edges of which extend in alinement with the edge 9 of the base. A strip of relatively thick rubber 11 is inserted within the channel member 10 and secured by means of rivets 12, passing entirely through the pan base 5, strip 11 and the channel member 10. This strip 11 extends entirely across the open front edge of the base 5 and has its outer end tapered to a point as illustrated at 13.

By providing a thickness of rubber at the rear of the strip 11 a certain rigidity is imparted to the latter, while the front part, 70 by virtue of the taper to form the point 13, imparts resiliency, so that the strip 11, when the same is forced in contact with the floor by pressure upon the handle 7, will adhere to the floor or surface and consequently no dust or dirt can pass under the pan.

In the modification, illustrated in Fig. 3 the front edge of the base 5 is submitted to operation of a stamping press which shears 80 the metal as at 14 and forms spring lips 15 and 16. Each alternate lip is pressed outwardly to provide for the reception of the rubber or fabric strip 17 between the said lips 15 and 16.

For holding the strip 17 in position between the lips 15 and 16, I provide a series of staples 18, having extensions 19 and 20 extending through lips 15 and 16 and the strip 17. Washers 21 are inserted over the 90 extensions 20 and the ends of the said extensions 19 and 20 are upset as at 22, so that the strip 17 is firmly held between the lips 15 and 16.

Likewise, the resilient strip of material 95 tapered to a point as at 23 and rivets 24 are passed through the lips 15 at each end of the pan to further hold the strip 17 in position thereon.

It is obvious, that rubberized packing or 100 other material of requisite resiliency and efficiency may be employed in lieu of the rubber strips 11 and 17.

From the foregoing it is thought that the construction of my invention will be clearly 105 understood, and, therefore, a more extended explanation has been omitted.

Having thus described the invention what I claim as new is:—

As a new article of manufacture, the here- 110 in described dust pan comprising a base, the said base having its edge portion sheared

to form a series of alternately disposed lips, each alternate lip adapted to be bent outwardly of the next succeeding lip, said lips being resilient, a strip of resilient material 5 having its end received between said lips, washers bearing against said material adjacent the adjacent edges of separated lips, and staples having extensions adapted to

pass through the said extensions and resilient lips and resilient strip.

In testimony whereof I affix my signature in the presence of two witnesses.

ARTHUR McCALLAN.

Witnesses:

M. McMILLAN,
E. LITTLE.
